UNITED STATES PATENT OFFICE.

WILLIAM J. FRYER, JR., AND GEORGE H. JOHNSON, OF NEW YORK, N. Y.;
SAID JOHNSON ASSIGNOR TO SAID FRYER.

IMPROVEMENT IN FIRE-PROOF MANSARD ROOFS.

Specification forming part of Letters Patent No. 141,215, dated July 29, 1873; application filed May 14, 1873.

To all whom it may concern:

Be it known that we, WILLIAM J. FRYER, Jr., and GEORGE H. JOHNSON, both of New York, in the county of New York and State of New York, have invented a new and Improved Fire-Proof Mansard Roof; and we do hereby declare the following to be a full, clear, and exact description of the same, reference being had to the accompanying drawings making a part of this specification, in which—

Figure 1 represents an elevation of a Mansard roof; Fig. 2, a vertical section; and Fig. 3, a transverse section of the same.

Our invention relates to the construction of Mansard roofs fire-proof.

We will describe all that is necessary to a full understanding of our invention, and then clearly point it out in the claims.

A is a continuous metal bed-plate laid on top of the front brick wall. B is a metallic beam placed at the top line of the roof. C C are upright metal rafters bolted to the plate at bottom and to the beam at top; the whole thus forming a rigid metallic framework. D are hollow baked-clay tiles. E are ordinary slates, or imitation slates, placed on the outside of the tiles, and fastened thereto through the joints of the tiles. The baked-clay tiles are so formed on the ends f as to clasp the metallic upright rafters. The tiles are scored or roughened on the back to receive plaster finish. The slates on the outside are more to give the usual finished appearance than as an additional precaution against fire other than the tiles afford.

The outside of the tiles may be coated with Portland cement or other composition to give it a smooth or ornamental appearance.

An inside ventilation through the tiles can

be secured by leaving holes in the lower and upper row.

By combining the metallic frame-work and hollow baked-clay tile-filling and outside covering of slates we secure, first, an entirely fire-proof Mansard roof; second, one which is water-tight and damp-proof, the air-chamber rendering it cool in summer and warm in winter; third, a very light roof, and one which can be built up on any angle or curve.

On reference to the drawings it is apparent that the clasp of the tiles to the raking rafters secures to the tiles the lateral support necessary to form the angular or curved baked-clay Mansard roof. When the tiles and rafters are in position they act as abutments—the rafters to the tiles—transversely. The same form and principle of an arch can be formed of solid instead of hollow materials, keeping to the same external outlines.

Having thus described our invention, what we claim as new, and desire to secure by Letters Patent, is—

1. A fire-proof Mansard roof formed of a bed-plate, A, top beam B, uprights C, hollow baked-clay tiles, D, and slate E, applied to a Mansard roof in the manner specified.

2. The metallic vertical rafters C, in combination with the hollow baked-clay tiles D, constructed in the form shown, and for the purpose specified.

3. The hollow baked-clay tiles D and covering of slate E, combined as and for the purposes shown and described.
